GAS BURNER

Filed Nov. 15, 1929

UNITED STATES PATENT OFFICE

WILLIAM S. SHAW, OF BOYNE CITY, MICHIGAN

GAS BURNER

Application filed November 15, 1939. Serial No. 407,307.

My invention relates to gas burners and has particular reference to gas burners for use in stoves and the like.

In the gas burners now used in stoves there is a considerable waste of gas due to improper combustion and loss by radiation.

An object of my invention is to provide an improved gas burner having a casing of insulating material which will reduce loss of gas by radiation to a minimum and prevent the air currents from affecting the combustion of the gas.

Another object of my invention is to provide an improved gas burner which will greatly reduce loss of gas by improper combustion.

Another object of my invention is to provide an improved type of gas burner which will confine the flames and gases to the bottom of the pan to be heated and prevent the escape of heat and gases into the room.

Further objects will be apparent from the description and drawing forming a part of this specification.

25 In the drawing—

Figure 1 is a top plan view, partly in section, showing my improved gas burner; and

Fig. 2 is a sectional view, partly in elevation, taken on the line 2—2 of Fig. 1.

30 Referring more particularly to the drawing in detail, 1 is the gas intake pipe having a valve 2 for regulating the flow of gas. The end of the pipe 1 is joined with a primary air valve 3 which is connected to the burner pipe 4 and which in turn communicates with the gas burner plate 5. The gas burner plate 5 is provided with lugs 6 for supporting a cylindrical casing 7 which may be of any heat-insulating material but is preferably of asbestos. The casing 7 is shown as being supported not only by the lugs 6 but by the burner pipe 4 over which it may be placed. On the inside of the casing 7 are

45 lugs or ribs which may be integral with the casing or may be attached thereto. The lugs 8 support a perforated plate 9, preferably of cast iron, which fits inside the casing 7 tightly against the sides thereof. This plate is pro-

50 vided with upwardly tapering holes 10 direct-

ly above the gas outlet orifices 11 in the burner plate 5.

The perforated plate 9 is spaced above the burner plate 5 so as to form below the same a mixing chamber for the mixture of the gases 55 emerging from the openings 11 and secondary air which is drawn up through openings 12 in the burner plate at the bottom of the casing 11. It has been found most satisfactory to position the perforated plate about 60 halfway between the burner plate 5 and the vessel on the stove to be heated.

The casing 7, which may be made in various sizes so as to fit various burner plates, is of such a height that, when in place, the top 65 thereof will extend to within about a quarter of an inch of the vessel to be heated.

In order to operate the gas burner the valve 2 is opened allowing gas from the intake pipe 1 to enter the burner pipe 4. In 70 the burner pipe the gas is mixed with primary air which is admitted through the primary air valve 3. This mixture of gas and air emerges from the orifices 11 into the mixing chamber between the top of the burner 75 plate 5 and the perforated plate 9. While in this chamber this gas and air is further mixed with secondary air which is drawn up through the openings 12 in the burner plate at the bottom of the casing 7. This mixture 80 then passes up through the tapering openings 10 in plate 9, being ignited above said plate. The ignition of the gases causes the plate 9 to be heated and as the gas goes up through the tapering openings 10 it is heated so as to 85 form a better mixture and insure a more perfect combustion. It is also evident that as more gas is admitted more secondary air will be drawn up due to the suction caused by the projected gas. Thus, the amount of air 90 mixed with the gas is automatically regulated by the flow of the gas. It is also evident that as the heat and gases are confined vertically by a casing of non-heat conducting material practically all the heat will be directed 95 against the bottom of the pan and vessel to be heated, thereby minimizing any losses due to radiation and resulting in a more efficient burner.

Although I have described but one embodiment—

ment of my device many modifications may be made without departing from the spirit of my invention. Therefore, I do not wish to be limited to the specific form shown.

I claim:

5. 1. The combination with a gas burner plate having gas outlet orifices, of a tubular casing of heat insulating material, a perforated plate adapted to fit inside said casing against the inner side thereof and means to sustain said perforated plate a distance above said burner plate to form a mixing chamber. 70
10. 2. The combination with a gas burner plate having gas outlet orifices, of a tubular casing of heat insulating material, a circular perforated plate adapted to fit inside said casing against the inner side thereof, and means to sustain said perforated plate a distance above said burner plate to form a mixing chamber. 75
15. 3. The combination with a gas burner plate having gas outlet orifices, of a cylindrical casing of heat insulating material, a circular perforated plate adapted to fit inside said casing and adjacent the sides thereof, having perforations directly above the orifices in said burner plate, and means to sustain said perforated plate a distance above said burner plate to form a mixing chamber. 80
20. 4. The combination with a gas burner plate having gas outlet orifices, of a cylindrical casing of heat insulating material disposed around and above said burner plate, a circular perforated plate adapted to fit inside said casing and adjacent the sides thereof, having perforations directly above the orifices in said burner plate, and means to sustain said perforated plate a distance above said burner plate to form a mixing chamber. 85
25. 5. The combination with a gas burner plate having gas outlet orifices, of a cylindrical casing of heat insulating material disposed around and above said burner plate, a circular perforated plate adapted to fit inside said casing and adjacent the sides thereof, having perforations directly above the orifices in said burner plate, and means inwardly projecting from said casing to sustain said perforated plate a distance above said burner plate to form a mixing chamber. 90
30. 6. The combination with a gas burner plate having gas outlet orifices, of a cylindrical casing of heat insulating material disposed around and above said burner plate, a circular perforated plate adapted to fit inside said casing and adjacent the sides thereof, having perforations directly above the orifices in said burner plate, and means inwardly projecting from said casing to sustain said perforated plate a distance above said burner plate to form a mixing chamber. 95
35. 7. The combination with a gas burner plate having gas outlet orifices, of a cylindrical casing of heat insulating material disposed around and above said burner plate, a circular perforated plate adapted to fit inside said casing and adjacent the sides thereof, having perforations directly above the orifices in said burner plate, and lugs projecting inwardly from said casing to sustain said perforated plate a distance above said burner plate to form a mixing chamber. 100
40. 8. The combination with a gas burner plate of a cooking stove, of a tubular casing of heat insulating material, a perforated plate adapted to fit inside said casing and against the sides thereof, having perforations directly above the orifices in said burner plate, and lugs projecting inwardly from said casing to sustain said perforated plate a distance above said burner plate to form a mixing chamber. 105
45. 9. The combination with a gas burner plate of a cooking stove, of a tubular asbestos casing maintained in position over said burner plate by means thereon, a cast iron plate adapted to fit inside said casing and adjacent the sides thereof, having upwardly tapering vents directly above the orifices in said burner plate, and lugs projecting inwardly from said casing to sustain said perforated plate a distance above said burner plate to form a mixing chamber. 110
50. 10. The combination with a gas burner plate of a cooking stove, of a tubular casing of heat insulating material supported by said burner plate, a perforated plate adapted to fit inside said casing, and means for sustaining said perforated plate a distance above said burner plate to form a mixing chamber. 115
55. 11. The combination with a gas burner plate of a cooking stove, of a cylindrical casing of heat insulating material supported by said burner plate, a perforated plate adapted to fit inside said casing, and means for sustaining said perforated plate a distance above said burner plate to form a mixing chamber. 120
60. 12. The combination with a gas burner plate having gas outlet orifices, of a tubular casing positioned about said plate and extending upwardly therefrom, and a perforated plate fitting within said tubular casing against the inner surfaces thereof at a distance above said burner plate whereby said perforated plate and said tubular casing form a mixing chamber above said burner plate, said chamber communicating with the outside atmosphere below said perforated plate for supplying air to said chamber. 125
65. 13. The combination with a gas burner plate having gas outlet orifices, of a tubular casing of heat insulating material fitting 130
70. 7. The combination with a gas burner plate

- about said burner plate and extending upwardly therefrom, and a perforated plate fitting within said tubular casing against the inner surfaces thereof at a distance above said burner plate whereby said perforated plate and said tubular casing form a mixing chamber above said burner plate.
14. The combination with a gas burner plate having gas outlet orifices, of a tubular casing of heat insulating material fitting about said burner plate and extending upwardly therefrom, and a perforated plate fitting within said tubular casing against the inner surfaces thereof at a distance above said burner plate whereby said perforated plate and said tubular casing form a mixing chamber above said burner plate, said chamber communicating with the outside atmosphere for supplying air to said chamber.
15. The combination with a gas burner plate having gas outlet orifices, of a tubular casing of heat insulating material fitting about said burner plate and extending upwardly therefrom, a perforated plate fitting within said tubular casing against the inner surfaces thereof at a distance above said burner plate whereby said perforated plate and said tubular casing form a mixing chamber above said burner plate, and an air supply means communicating with the outside atmosphere through the lower end of said casing for supplying air to said chamber.
16. The combination with a gas burner plate having gas outlet orifices, of a tubular casing of heat insulating material fitting about said burner plate and extending upwardly therefrom, a perforated plate fitting within said tubular casing against the inner surfaces thereof at a distance above said burner plate whereby said perforated plate and said tubular casing form a mixing chamber above said burner plate, and an air supply means extending through said burner plate for connecting said chamber with the outside atmosphere.
17. A gas burner comprising a burner plate having gas outlet orifices, a tubular casing of heat insulating material fitting about said burner plate and extending upwardly therefrom, and a perforated plate fitting within said casing against the inner surfaces thereof at a distance above said burner plate to form a mixing chamber, said burner plate being shaped to permit the atmosphere to enter said chamber through the bottom of said casing.
18. The combination with a gas burner plate having gas outlet orifices, of a tubular casing positioned about said plate and extending upwardly therefrom, and a perforated plate fitting within said tubular casing against the inner surfaces thereof at a distance above said burner plate whereby said perforated plate and said tubular casing form a mixing chamber above said burner plate,
- and air supply means communicating with the outside atmosphere through the lower end of said casing for supplying air to said chamber.
- In witness whereof, I have hereunto subscribed my name.
